UNITED STATES PATENT OFFICE.

CHARLES DE LUKACSEVICS, OF NUTLEY, NEW JERSEY, ASSIGNOR TO DANE MANUFACTURING COMPANY, OF NEWARK, NEW JERSEY, A CORPORATION OF NEW JERSEY.

SIPHON-HEAD.

1,151,447.

Specification of Letters Patent. Patented Aug. 24, 1915.

Application filed July 20, 1914. Serial No. 852,013.

To all whom it may concern:

Be it known that I, CHARLES DE LUKACSEVICS, a citizen of the United States, residing at Nutley, in the county of Essex and State of New Jersey, have invented new and useful Improvements in Siphon-Heads, of which the following is a specification.

This invention relates to improvements in siphon heads wherein a spring held valve 10 operates in a cavity formed in the head proper and coacts with a valve seat provided at the upper end of said cavity.

The problem which presents the greatest difficulty in siphon head construction is to provide a simple and practical siphon head which combines the advantages (1) of being absolutely sanitary, (2) of not being particularly liable to breakage or derangement, and (3) of efficiently and reliably 20 preventing the escape of the highly volatile carbonic acid gas with which the water is charged. This problem is satisfactorily dealt with by certain prior constructions, as examples of which may be mentioned, the 25 constructions shown in my prior U. S. Patent No. 1,040,226 of Oct. 1, 1912, in my pending U. S. application, Serial No. 801,224, and in the pending application of William P. Dilts, Serial No. 827,389.

30 In the three prior constructions referred to, the valve organizations have certain common characteristic features, viz., the formation of the valve stem of a metal bar for the purpose of strength, the covering of the 35 metal bar with a sleeve of hard non-corrosive material for the purpose of sanitation, the provision of a non-corrosive valve head at the lower end of said sleeve, the said valve head having a yieldable 40 engaging surface, and the provision of a relatively hard valve seat for coöperation with the engaging surface of the valve head. While the valve organization as just explained is practical and satisfactory for the 45 principal purposes in view, it is, as carried out in the prior constructions identified, open to objection, in that its assemblage is somewhat difficult, requiring particular care and skill and taking up, in the aggregate, 50 for the daily output of an average plant, a substantial amount of time.

The present invention which relates to the general type of construction, exemplified in the three prior constructions above identified, is concerned especially with the organi-

zation of the valve and its immediate appurtenances and its object is to provide a valve organization which while serving the advantages above stated, in the same measure as the prior devices, may be produced with 60 greater facility, in less time, and with less liability of being defective on account of the lack of skill or care on the part of the workmen.

Two embodiments of the invention are 65 shown by way of example in the accompanying drawings, in which:

Figure 1 is a sectional view showing the features of the invention in connection with a siphon head of the general construction 70 shown in my said pending application, Serial No. 801,224. Figs. 2 to 5 illustrate details of the valve seat. Figs. 6 and 7 illustrate details of the valve and its stem. Fig. 8 is a sectional view showing the features of 75 the invention in connection with a siphon head of the general construction shown in the said pending application of William P. Dilts, Serial No. 827,389. Fig. 9 shows the valve seat in section and bottom plan, and 80 Figs. 10 and 11 illustrate details of a slightly modified valve construction.

Similar characters of reference designate 85 corresponding parts throughout the several views.

The construction shown in Fig. 1 is generally similar to the construction shown in my said pending application and in common with the latter includes a head 1, preferably of porcelain, having its lower end in the 90 form of an enlarged socket 2, which fits over the bottle neck 3 and is held in position, for example, by securing rings 4 and 5; a bell-shaped or generally globular cavity 7 opening from the inner end of the socket 2; a liquid passage 8 extending upwardly from the cavity 7 and having the usual liquid discharge duct 9; a bell-shaped member 10 of hard or relatively hard non-porous material, such as rubber, having a circumscribing 100 flange 11 to engage over the mouth of the bottle, said member 10 providing a cavity internal to the cavity 7 and communicating at one end with the liquid passage 8 and at its other end with the siphon tube 6; a hard 105 rubber sleeve 13 carrying the siphon tube 6 and threaded in a depending flange 12 formed as a part of the member 10; a gasket 14 arranged between the member 10 and the bottle neck; and a gasket 15 arranged 110

between the member 10 and the cavity 7. The foregoing elements being old, need no description other than the mere enumeration thereof above given.

5 The member 10 carries within its internal cavity a seat 16 for a valve 17 and, while this valve and its seat are similar as regards relation to the valve and valve seat shown in my said pending application, they are substantially different as regards their structure. The elements of the valve are a metal core 18 which has a roughened or corrugated surface and a fork-like enlargement 19 at its lower end; and a hard non-porous and non-corrosive sleeve 20, preferably composed of rubber which is cast upon the core 18 and completely incloses the same except for a short projecting portion at the upper end of said core. The sleeve 20 terminates at its 15 lower end in an enlarged relatively hard valve head 21 which is reinforced by the enlargement 19 and is suitably formed to efficiently discharge the functions of a siphon head valve. The head 21 is complete, in itself, as the valve and the engaging valve surface is in fact the surface of said head, such valve surface having a conical outline, and uniformly engaging the conical inner circumferential face of the valve seat 16 substantially throughout the area of said seat.

The sleeve 20 and the head 21 integral therewith being cast upon the stem 18, take a secure grip upon the surface corrugations of said stem.

30 In the construction shown in my said pending application, the seat for the valve is formed as an integral part of the member 10. In the present construction, the valve seat consists of a ring of soft rubber cast within the cavity of the member 10 at the upper end thereof.

The valve is operated by a spring held button 22 which, in the way in which it is secured to the projecting or uncovered upper end portion of the stem 18 and in all other respects is similar to the construction shown in my said pending application.

Fig. 8 shows the features of the present invention in connection with the construction shown in the said pending application of William P. Dilts, Serial No. 827,389. In this case, the siphon head 25 is composed of compressed material, such for example, as that used for electrical insulation and known under the various trade names of "bakelite," "condensite" and "hi-heet." The siphon is held upon the bottle neck in the

usual manner and is provided with an internally threaded valve chamber 26 in the lower portion of which is fitted a sleeve 27 carrying the siphon tube 6. The valve and its stem are of the construction already described herein and the valve head co-operates with a soft rubber valve seat 16^a cast in the chamber 26 at the upper end thereof and securely gripping its threads.

The valve and valve stem construction shown in Figs. 6 and 7 is applicable to either of the siphon head constructions shown. The same is true of the valve stem construction shown in Figs. 10 and 11. The only difference between the two valve constructions is a colorable one involving the form or design of the core 18. In both cases, the surface of the core is corrugated and is securely gripped by the sleeve and valve head cast thereon.

The valve herein described may be manufactured with facility, the only operation involved, being that of casting the hard non-porous and non-corrosive envelop or sleeve and the valve head integral therewith upon the metal core. The relatively soft valve seat may be readily cast in the cavity provided therefor and efficiently co-operates with the hard valve head in preventing the escape of gas.

Having fully described my invention, I claim:

In combination, a siphon head having means for attachment upon the bottle neck and having a cavity adapted to align with said neck, and a liquid duct extending upwardly from said cavity, a valve organization comprising a core, and a valve head of hard non-porous and non-corrosive material cast upon the lower end of said core and having a conical seating face, an elastic valve seat secured in said cavity for co-operation with said valve head and having a conical valve engaging face, and means for holding said valve normally against said seat, the valve head engaging with its hard outer surface directly against said seat substantially throughout the area of the conical face thereof.

In testimony whereof I have hereunto set my hand in presence of two subscribing witnesses.

CHARLES DE LUKACSEVICS.
